INVENTOR
GILBERT G. DAVIS

BY Fetherstonhaugh & Co

ATTORNEY

UNITED STATES PATENT OFFICE.

GILBERT G. DAVIS, OF VANCOUVER, BRITISH COLUMBIA, CANADA.

LOG RAFT AND MEANS OF LAUNCHING SAME.

Application filed September 22, 1922. Serial No. 589,786.

To all whom it may concern:

Be it known that I, GILBERT G. DAVIS, a resident of the city of Vancouver, in the Province of British Columbia, Canada, have invented certain new and useful Improvements in Log Rafts and Means of Launching Same, of which the following is a specification.

My invention relates to improvements in log rafts and apparatus for launching same, and refers in particular to that class of log raft set forth in Letters Patent of the United States of America, No. 1,142,239, granted to me on the 8th day of June, 1915.

In the patent above referred to, the bottom logs forming the floor of the rafts are flexibly connected side by side with wire ropes passing alternately over and under the logs and the top load is secured to this floor.

The object of my invention is to provide safe and simple means for securing tiers of logs to the raft to form a composite body, from which logs cannot be dislodged by the action of the seas through which it may be towed.

A further object is to provide means for constructing the log rafts above high water mark and subsequently launching them.

My invention consists of a method of binding the tiers of logs forming the raft, one to the other and of a plurality of cradles in which the raft may be formed and tracks along which the cradles and the raft may be slid into deep water, as will be more fully described in the following specification.

Fig. 1 is a sectional view of my raft floating.

Fig. 2 is a sectional view of the raft showing one of the cradles in which it is formed.

Fig. 3 is a perspective view of a raft and launching apparatus.

In the drawings like characters of reference indicate corresponding parts in each figure.

In these drawings 1 indicates the logs forming the floor of the raft, which are flexibly connected together and to the side logs 2 by wire ropes 3 interwoven at intervals apart around the logs. The construction thus far described is set forth in my patent previously referred to.

4, 5, 6 and 7 are successive tiers of logs forming the top load of the raft 4^x, 5^x, and 6^x being the outside logs of their respective tiers. 8 is a pole running lengthwise of the raft and is centrally positioned on the top

tier of logs, which pole has circumferential grooves 9 spaced apart that the binding ropes may be freely passed under the pole and readily tightened thereon by any desired means.

10 indicates a plurality of ropes which are each secured at their outer ends by clips 11 and which are used to bind the several tiers to the side logs of the tier below, and to the pole 8 in the following manner.

For the purpose of more clearly showing in Fig. 1 the course that the ropes follow in binding each tier of logs to the raft, the rope binding tier 4 is shown in solid line, 70 the rope binding tier 5 is shown in open line, and the rope binding tier 6 is shown lightly cross hatched.

In tier 4 a rope 10 is passed under a side log 2 and clipped upon itself as at 11^A, if 75 desired the starting end of the rope is left long enough to pass around the pole 8 and fastened thereto, the rope is then laid over the tier 4 and passed under log 2 of the opposite side of raft floor and preferably 80 clipped upon itself adjacent such side log, the end of the rope at the completion of the raft being passed under the pole 8 and in one of the grooves 9, it is then brought over the log, tightened up as desired and fastened 85 upon itself by the clip 11^B.

Tier 5 is secured in a similar manner to the side logs 4^x of tier 4, though the binding of each tier will commence on the opposite side to that of the previous tier, the 90 binding rope of tier 5 being first clipped as at 11^C and after passing around pole 8 finally clipped adjacent thereto by the clip 11^D.

The tier 6 is bound to the side logs 5^x 95 by a rope 10 which is first clipped at 11^E and finally clipped at 11^F.

It may be deemed sufficient where heavy seas are not likely to be encountered, to dispense with the pole 8 and to clip the ends 100 of the binding ropes 10 adjacent each of the side logs that they pass around, yet where extra rough towing weather is contemplated, I may desire to add a further rope 10, see Fig. 3, which would be first attached to the pole 8, passed downwardly between the side log 2 and the raft, then around the side log, then under the floor of the raft and around the opposite side log 2 in a similar manner and from thence taken up and around the pole 8 and clipped 105 as hereinbefore described.

The apparatus for launching the raft of logs is particularly shown in Figs. 2 and 3, in which 12 indicates a plurality of tracks which are laid parallel to each other on the sloping ground and extending into the water, each track being preferably formed of one small diameter log 13 and a larger log 14 on either side thereof to form a groove 15. 16 are skids of substantially similar length to the raft to be launched and are laid in the groove 15 of the tracks 12 for endwise movement therein. 17 indicates in general, a cradle in which the log raft is formed, 18 being a bolster secured transversely to the skids 16, by the straps 19, which bolster is provided with a plurality of notches 20 on its upper edge to receive the bearers 21 and struts 24. 21 are bearers on which the log raft is formed the lower and inner ends of which are scarfed to rest within a pair of notches 20, the lower edges of the bearers being provided with notches 22 to engage the upper ends of the strut members. 23 are knee pieces carried upon the bolster 18 and bearers 21 that the raft floor may be formed substantially concave in cross section. 24 is a plurality of struts scarfed at their opposite ends to engage the notches 20 and 22 of the bolster and the bearers and to prevent their displacement during the loading of the logs upon the cradle 17.

25 is a plurality of short ropes one end of each of which is suitably secured to the bolster 18 and the opposite end being secured to the foot of a strut or a bearer member so that on the collapsing of the cradles subsequent to the launching of the raft, the several structural members of the cradle can be withdrawn from the water and the cradle quickly reassembled for reuse. 26 is a rope attached to a bolster for withdrawing the launching device from the water.

Having thus described the various parts of my invention, I will now briefly explain its use.

The skids 16 and bolsters 18 are set in a suitable position on the track 13 and the several cradles assembled, in the manner shown, and logs are loaded thereon to form a raft, and when ready to launch a rope 26 is preferably attached to the bolster nearest the upper end of the track.

The skids with their cradles and the raft are then slid downwards of the track in the manner of launching a ship, the above mentioned rope being paid out until the several cradles are fully submerged and the raft is freely floating, when a pulling strain is exerted upon the rope 26, the impetus of the floating mass of the raft, running counter to the pull of the rope, collapses the cradles that they may be readily withdrawn from under the raft and brought back onto the track and reassembled for further loading.

What I claim as my invention is:

1. In a log raft, a raft floor, logs arranged in tiers carried upon the floor, means for connecting the lowermost tier to the floor and each successive tier individually to the next underlying tier.

2. In a log raft, a raft floor, logs arranged in tiers carried upon the floor, a pole extending longitudinally of the raft top, a single means for securing the lowermost tier to the raft floor and to the top pole, and a single means for connecting each successive tier to the next underlying tier and to the top pole.

3. In a log raft, a raft floor, logs arranged in tiers carried upon the floor, a pole extending longitudinally of the raft top and binding means extending at each side of the raft and secured to the top pole for holding the logs of the lowermost tier together and for securing the tier as a whole to the raft, and similar binding means connecting each tier individually to an underlying tier.

4. In a log raft, a raft floor, logs arranged in tiers carried upon the floor, a pole extending longitudinally upon the top of the raft, a flexible binder extending between each tier and connected at one end to one side of the raft and intermediately of its length to the opposite side of the raft and at its opposite end to the top pole.

5. In a log raft, a raft floor formed with longitudinal side logs, logs arranged in tiers carried upon the floor, a pole extending longitudinally of the raft top, a flexible binder secured at one end around one side log of the raft floor and extending over the lowermost tier around the side log at the other side of the raft floor and from thence up the side of the raft to be secured around the top pole, and a flexible binder extending between each pair of adjacent tiers and connected at one end to the side logs of each tier and alternately at each side of the raft and at the opposite end extending alternately at each side of the raft and secured to the top pole.

6. A log raft launching apparatus comprising a runway skids slideable thereon, log bearing devices flexibly connected together and adapted to extend crosswise of the skids and upon which the raft is carried, a pull rope, withdrawable means supporting the bearing devices in their bearing position and adapted to be withdrawn when strain is exerted on the pull rope whereby the bearing devices are collapsed.

Dated at Vancouver, B. C., this 16th day of August, 1922.

GILBERT G. DAVIS.
